UNITED STATES PATENT OFFICE.

JOHN M. CAGE, OF LONG BEACH, CALIFORNIA, ASSIGNOR, BY MESNE ASSIGNMENTS, TO
L. A. SUBMARINE BOAT COMPANY, OF LONG BEACH, CALIFORNIA.

STEERING AND PROPULSION FOR SUBMARINES.

1,281,132.

Specification of Letters Patent.

Patented Oct. 8, 1918.

Application filed October 26, 1914. Serial No. 868,569.

To all whom it may concern:

Be it known that I, JOHN M. CAGE, a citizen of the United States, residing at Long Beach, in the county of Los Angeles, State 5 of California, have invented new and useful Improvements in Steering and Propulsion for Submarines, of which the following is a specification.

This invention relates to the subject matter 10 of steering and general control of submarines; being in the nature of a continuation along these specified lines of my former applications, Serial Numbers 634,784 and 738,- 745, filed June 22, 1911, and Dec. 26, 1912, 15 respectively.

The fundamental distinction of this present invention is the combination in a submarine of propulsion mechanism including a propeller arranged near the bow of the vessel and control mechanism including rudders arranged near the stern of the vessel (or forward and rearward of the center of buoyancy or center of gravity, respectively). By extended experimentation and trial I have 25 found that such a combination leads to distinctive and novel results in the control of a submarine; and I have found that this method of control has utilities in a submarine which it has not in an ordinary surface 30 vessel. I am aware that surface vessels have been propelled with propellers forward of the rudders; but in surface vessels such a combination and such control does not lead to the distinctive results which it leads to in 35 a submarine. The peculiarities of action and the efficiency of control due to my arrangement are described in the following specification. In the accompanying drawings I have shown an adaptation of my invention 40 to a typical submarine, in which drawings Figure 1 is an elevation, with parts broken away, showing a submarine equipped with my invention, and Fig. 2 is a plan showing the same.

45 In the drawings the numeral 10 designates a hull or body of a submarine vessel with bow 10^a and stern 10^b. Within the hull, at a position depending upon the interior arrangement and general design, I place my 50 power plant, such as internal combustion engines indicated at 11. These engines are preferably in pairs and drive a pair of propeller shafts 12 carrying propellers 13 on their forward end near the bow of the boat

and forward of the center of gravity or the 55 center of buoyancy thereof.

The steering mechanism may include both vertical control and horizontal control rudders 14 and 15. The horizontal control rudder 15 is mounted on a vertical pivot as shown and may be controlled from a wheel 16 through the medium of shafting or other connection 17. The vertical control rudders may be mounted upon a common horizontal axis 18 and operated from a wheel 19 through 60 the medium of shafting and other connections 20. Both of these control rudders are placed near the stern well behind the center of gravity and center of buoyancy of the 65 hull.

The peculiar efficiency of control due to my combination and arrangement relates particularly to the accuracy, efficiency and perfection of vertical control as to rising and driving of the submarine. I will explain 70 how the results of my system are different from those of the ordinary systems of controlling and propelling submarines. In the ordinary submarine the vessel is pushed from behind instead of being pulled in front. 75 When an ordinary submarine is caused to dive by the use of its diving rudders, if the nose of the boat sinks downward beyond a certain angle, the boat being propelled forwardly, the action of the water above and ahead of the boat "banking up" on the submarine causes the submarine to very quickly 80 dive more steeply and to ultimately dive practically straight downwardly. This has 85 been a more or less common experience, well 90 known to operators of submarines. It is the ordinary practice in submerging or diving a submarine to submerge the boat on an even keel; it is dangerous to submerge the boat on an uneven keel; or while the boat is being 95 propelled. The cause of this action seems to be essentially due to the fact that the boat is pushed or propelled from behind and that, when the boat starts to dive, the rear propelled end tends to move forwardly over the 100 bow, thus tending to increase the angle at which the boat is diving. When this angle has increased to a certain amount, the boat becomes uncontrollable and will go on diving in spite of all that can be done with the 105 rudders.

When my submarine is running on the surface, say, and it is desired to dive below

the surface, this can be readily accomplished by simple manipulation of the diving or vertical control rudders. In the ordinary submarine, if the dive is effected by the rudders 5 alone, the effect is to sink the nose of the vessel without raising the stern; in so far as the vessel can be said to turn about any fixed point, the ordinary submarine turns about its stern or about its point of propulsion. When 10 the dive is effected under my arrangement, the stern rises to an appreciable degree as the dive starts and the stern is then pulled under water by the propellers driving the boat on a course parallel to its own axis. 15 The diving action is very similar to that of a fish when it swims at the surface and suddenly dives under, the tail appearing for a brief instant and then being drawn under. In other words, my submarine turns about 20 a point forward of the stern.

With my arrangement it is possible to submerge a submarine traveling at full speed without changing the ballast; it is possible to do this almost instantaneously; it is 25 possible to hold the submarine, while running, below the surface and to come to the surface momentarily without lightening the ballast. And it is possible, and has been proven by experiments and tests, to dive at 30 a very steep angle and to keep the submarine under perfect control at all times. This ability to dive almost instantaneously and to come to the surface whenever desired, is of extreme importance in submarine maneuvering. Conditions of actual warfare 35 require that a submarine shall be able to quickly submerge to avoid danger and to quickly come to the surface when it is necessary to obtain bearings; and it is also of 40 very great importance, and gives a submarine a great advantage, to be able to travel awash and to utilize atmospheric air instead of stored air, and at the same time to be able to dive quickly when necessary. The 45 ordinary submarine must travel a great proportion of the time submerged, when in actual warfare, due to the fact that it cannot submerge but slowly. Where there is a chance of running into danger, the ordinary submarine must travel submerged; and this fact greatly limits its useful radius of 50 action. On the other hand, my submarine may travel awash except when in actual danger and even then if may momentarily 55 come to the surface from time to time to ob-

tain bearings, because it can dive out of danger before there is time for it to be damaged.

Having described my invention, I claim:

1. In submarines, a hull, driving mechanism therefor including propeller exclusively forward of the center of gravity of the hull, and steering mechanism including a vertical control rudder exclusively to the rear of the center of gravity of the hull. 60

2. In submarines, a hull, driving mechanism therefor including a propeller exclusively forward of the center of gravity of the hull, and steering mechanism therefor including vertical and lateral control rudders exclusively to the rear of the center of 70 gravity of the hull. 65

3. In submarines, a hull, driving mechanism therefore including a propeller exclusively near the bow, and steering mechanism therefor including a vertical control rudder 75 exclusively near the stern. 70

4. In submarines, a hull, driving mechanism therefor including a propeller exclusively near the bow, and steering mechanism therefor including vertical and lateral control rudders exclusively near the stern. 80

5. In a submarine boat, the combination with a hull having rudders mounted on a horizontal axis at each side of the hull adjacent the stern thereof, of propellers for the hull mounted near the bow thereof in substantially the same plane as the axis of said rudders, said rudders and propellers being disposed one in the way of the other so that currents set up by said propellers 85 will be carried into the zone of action of said rudders. 90

6. In a submarine boat, the combination with a hull having rudders mounted on a horizontal axis at each side of the hull exclusively adjacent the stern thereof, of propellers for the hull mounted exclusively near the bow thereof in substantially the same plane as the axis of said rudders, said rudders and propellers being disposed one in the way of the other so that currents set up by said propellers 95 will be carried into the zone of action of 100 said rudders. 100

In witness that I claim the foregoing I have hereunto subscribed my name this 16th day of October 1914.

JOHN M. CAGE.
